UNITED STATES PATENT OFFICE.

GUSTAF G. JOHNSON, OF WISHAW, PENNSYLVANIA, ASSIGNOR TO I. N. RODKEY, OF SPANGLER, PENNSYLVANIA.

EXTENSION CAR-STEP.

No. 820,876.

Specification of Letters Patent.

Patented May 15, 1906.

Application filed September 8, 1905. Serial No. 277,493.

To all whom it may concern:

Be it known that I, GUSTAF G. JOHNSON, a citizen of the United States, residing at Wishaw, in the county of Jefferson and the State of Pennsylvania, have invented a new and useful Improvement in Extension Car-Steps, of which the following is a specification.

This invention relates generally to car-steps, and more particularly to an extension or extensible step by means of which a one-quarter step can be added to the three steps ordinarily arranged in connection with a railway-car platform.

It frequently happens that a car is stopped at a point where the lowest step is at a considerable elevation above the ground, and it is with the object of providing an additional step which can be quickly and easily lowered when desired and as quickly and easily raised when not in use that I have devised my present invention; and the invention consists in the novel features of construction, combination, and arrangement whereby these objects are accomplished.

In the drawings forming part of this specification, Figure 1 is a perspective view showing my extension car-step lowered. Fig. 2 is a similar view showing the same raised. Fig. 3 is a perspective view showing the under side and also illustrating the operating mechanism. Fig. 4 is a sectional view showing the step raised. Fig. 5 is a sectional view showing the step lowered. Fig. 6 is a view illustrating the means for locking the step in a raised position.

Referring to the drawings, A indicates the car-platform, and B the ordinary fixed steps extending therefrom.

C designates the extension-step having a metallic portion D connected to the under side of the step, said portion extending upwardly upon the under side of the steps proper and terminating in box-loops D', which slide upon the bars E, secured at their upper ends to the timbers of the car-platform and at their lower ends to a horizontal strip F, secured upon the under side of the step B. The central angled bar G is connected to the under side of the step C, said bar passing upwardly through a guide G', arranged upon

the horizontal strip F, the upper end of said central bar being pivotally connected to a lever H, pivoted intermediate its ends to the rear of the fixed steps, the opposite end of said lever being connected to an operating rod or handle which passes upwardly through the end sill of the car-platform and is provided with ratchet-faced projection I' adjacent to its upper end and terminates in an eye or ring I², which provides a suitable hand-grip. The upper end of this eye or handle works through the slotted plate K, and the ratchet projections I² are adapted to engage in said plate, and a spring K' presses upon the said rod or handle for the purpose of normally holding the said projection into engagement with the said plate. This projection engages the plate when the handle or rod is forced downwardly and the step C raised. In order to disengage the projections from the plate, the rod or handle is thrown upwardly, pressing back the spring K', and the rod or handle can then be pulled upwardly, throwing the step C down, and in order to permit this movement of the handle I the connection between the rod or handle and lever is a loose one, as indicated. Guide-plates L are attached to each side of the step, said plates being slotted at L', in which guide-pins L² work. These guide-plates L are gradually tapered and work through the guide-loops L³, arranged upon the sides of the steps B, and the upper ends of the guide-plates are provided with downwardly-projecting stops L⁴, which engage the guide-loops L³ and limit the downward movement of the step C.

It will thus be seen that I provide a cheap and simple construction of car-step which can be readily attached to the car-steps now in use and which can be quickly and easily operated to raise or lower the step, as desired.

Having thus fully described my invention, what I claim as new, and desire to secure by Letters Patent, is—

The combination with main steps, of a supplemental step, guide-bars fixed to the main steps, bars attached to the supplemental step and having box-loops, a central bar, an

operating-handle, means connecting the handle and bar, said handle having ratchet projections adjacent its upper end, a slotted plate through which the upper end of the handle works, a spring adapted to hold said ratchet projections in engagement with the slotted plate, a slotted guide-plate carried

by the side of the steps and having a stop formed at its upper end, and guide-loops on the step side for said plates.

GUSTAF G. JOHNSON.
